UNITED STATES PATENT OFFICE.

GEORGE W. MUNDIE, OF PERU, ILLINOIS.

DRAFT-CONTROLLING MEANS FOR TANK HEATERS.

Application filed April 7, 1923. Serial No. 630,507.

To all whom it may concern:

Be it known that I, GEORGE W. MUNDIE, a citizen of the United States, residing at Peru, in the county of La Salle and State of Illinois, have invented certain new and useful Improvements in Draft-Controlling Means for Tank Heaters, of which the following is a specification, reference being had to the accompanying drawings.

10 This invention relates to tank heaters, and particularly to tank heaters of the character shown in Patent No. 908,182, of December 29, 1908, and No. 966,147, of August 2, 1910.

In heaters of this character there has been 15 provided a fire box with a grate and a flue leading from the upper end of the fire box, with a damper disposed just below the flue and resting upon one end of a baffle plate extending longitudinally of the heater and 20 adjacent the upper wall thereof, this baffle defining a return flue. When the fire is first started in a heater of this character, the damper is turned to such a position as will permit the products of combustion to 25 pass directly upward without going through the return flue and pass directly out through the discharge flue or smoke pipe. In heaters of this character as placed upon the market, this damper rests loosely upon a seat formed 30 at the inner end of the baffle and the damper is operated by a wire extending through the smoke pipe at the base thereof and connected to an arm on the damper. It has been found that in assembling this heater this damper 35 is very liable to be reversed in position upon its seat so that the arm instead of extending toward the opening through which the wire passes extends reversely thereto and this gives rise to troubles in the operation of 40 the device. Thus, for instance, if the damper is turned around from its correct position the diagonal shank of the damper holds the damper open at all times, letting all the heat go directly up the chimney and not diverting 45 the products of combustion through the return flue, as is necessary to secure proper heating results after the fire has been started. Furthermore, it has been found the case that the user loses the damper during the warmer months of the year when it is not necessary to operate the heater.

The object of the present invention is to do away entirely with this damper and provide means which does not require adjustment and which is permanently disposed in

position so that it cannot be lost, which will act when the fire is first built to conduct the products of combustion directly to the smoke pipe or outlet discharge flue and when the fire has become fully started will act to automatically cause the products of combustion to pass through the return flue and thus impede the passage of the combustion products and cause them to give out more heat to the water surrounding the tank.

The invention is illustrated in the accompanying drawings, wherein:—

Figure 1 is a side elevation of one section A of my heater looking at the inside face thereof;

Figure 2 is a section through both sections of the complete heater on the line 2—2 of Figure 1;

Figure 3 is a fragmentary top plan view of the complete heater.

Referring to these drawings, it will be seen that I have illustrated a tank heater of the general character shown in the patents before referred to. This heater is formed in two main sections A and B, these sections being identical and being formed with confronting marginal flanges whereby the sections may be joined to form the complete heater. These sections A and B are so formed as to provide a fire box 10 within which a grate 11 is normally disposed, there being a fuel chute 12 extending down into the fire box.

As illustrated in Figure 3, the upper portion of the heater casing is contracted in width to form a return flue 13. This return flue 13 opens into an upwardly extending circular discharge flue 14. The inner wall 15 of this discharge flue which is formed by the two sections A and B, as shown in Figure 2, has extending from its lower edge the downwardly and laterally extending damper wall 16. This wall is, of course, formed in two sections, one section being cast with the section A of the casing and the other section being cast with the section B. A baffle 17 extends in one direction from the lower end of the wall 16, this baffle being formed in two sections. Immediately above this baffle the return flue is constricted, as at 18, to form a relatively narrow passage which merges into the relatively large portion of the return flue 13. Heaters of this type are all formed with the baffle 17 and the contracted portion 18 immediately above

it merging into the return flue and hence the formation of the heater in this regard does not require any particular description.

5 My invention consists in providing the damper wall 16 and forming in this wall the elliptical opening 19. This opening has its major axis extending transversely of the heater and the lower edge of this opening is disposed just above the contracted portion

18. I have found by a series of tests lasting over a number of years that the elliptical form of opening is particularly necessary and that it is particularly necessary that this opening should be located just above the narrowed or contracted portion 18 and that the opening should have a major diameter of approximately $3\frac{3}{4}$ ", with a minor diameter slightly less than two inches. Of course, I do not wish to be limited to the exact situation of this opening or the proportions of the opening. Nevertheless I find an opening located as described and having the proportions stated to be particularly effective.

25 As before remarked, I do away entirely with the movable damper which is ordinarily located at the inner end of the baffle 17 and which is shiftable to permit all the products of combustion to pass up through the discharge flue 14 or to cause the products of combustion to pass beneath the baffle 17 and around and into the return flue and so out of the discharge flue. I have found by experiments conducted over a considerable time that the position of the hole 19 as shown secures the best results for the reason that the force of the draft around the return flue when the volume of the fire was increased to normal effectually prevented any draft through this opening 19 and best preserved the efficiency of the heating by the return flue. I have found also that if this opening is placed up higher than the position shown in Figure 1 it does not operate so well, presumably because the heat from the return flue is deflected by the solid plate below the opening 19 which deprives it of the necessary force to prevent inflow of products of combustion through the opening 19 in the flue 14. I have also found that forming this opening 19 elliptical in shape gives much better results than where the opening 19 is circular. This is due to the fact apparently that the shape of this opening spread out the draft passing through the opening which resulted in it being much more effectually closed when in normal operation from the fact, as I reason it, that the draft from the return flue has more area with less resistance to work against than if the opening were circular. It will be understood, of course, that when the fire is started the products of combustion will take

the shortest course and pass directly up through the opening 19 and through the flue 14. After the fire has been started, however, and combustion products are evolved in relatively large quantities, they will pass both ways, one current passing up through the opening 19 and the other current passing around the baffle 17 and so into the return flue 13, until the force of the draft around the return flue increases to its normal extent, at which time there is so much pressure of the products of combustion on one side of the opening 19 as to prevent the direct discharge of combustion products through this opening 19. 65 70 75

It will be seen that this invention simplifies the construction of heaters of this character, that it eliminates the movable damper plate with its attendant objections, and that it acts automatically to control the passage of the combustion products without the necessity of adjustment. 85

I claim:—

1. In a tank heater, a fire box, a discharge flue disposed immediately above the fire box, a wall extending downward from one wall of the discharge flue and having a draft opening therethrough, and a baffle extending transversely through the axis of the discharge flue and from the lower end of the wall and defining a return flue between it and the top of the heater. 90

2. In a tank heater, a fire box, a discharge flue disposed immediately above the fire box, a wall extending downward from one wall of the discharge flue and having a draft opening therethrough, and a baffle extending transversely through the axis of the discharge flue and from the lower end of the wall and defining a return flue between it and the top of the heater, the return flue immediately above the baffle being constricted for approximately the length of the baffle, the opening being disposed on a level slightly above the said constricted portion. 105

3. In a tank heater, a fire box, a discharge flue disposed directly above the fire box, a wall extending downward at an inclination from one wall of the flue and having a draft opening therethrough, and a baffle extending transversely of the axis of the flue and from the lower end of the wall and defining a return flue between it and the top of the heater, said return flue immediately above the baffle being laterally constricted for the length of the baffle, the opening being disposed above said constricted portion, said opening being elliptical and having its major axis disposed transversely of the heater. 110 115 120

In testimony whereof I hereunto affix my signature.

GEORGE W. MUNDIE.
